(57) **CLAIM**

The ornamental design for an electrical connector, as shown
and described.

DESCRIPTION

FIG. 1 is a perspective view of the front, top and right side
of the electrical connector showing our new design;
FIG. 2 is a perspective view of the front, bottom and right
side thereof;

FIG. 3 is a perspective view of the rear, top and left side
thereof;

FIG. 4 is a perspective view of the rear, bottom and left side
thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom view thereof; and,

FIG. 11 is an enlarged cross sectional view at 11-11 in FIG.
5 and at 11-11 in FIG. 9.

The broken line showing of the electrical connector is for the
purpose of illustrating portions of the electrical connector
and forms no part of the claimed design. The dashed-dotted
lines define the bounds of the claimed design and form no
part thereof.
